(57) **CLAIM**

The ornamental design for the jewelry arrangement, as shown and described.

DESCRIPTION

FIG. 1 is a perspective view of a first exemplary embodiment of a jewelry arrangement showing my new design;

FIG. 2 is an exploded perspective view thereof;

FIG. 3 is another exploded perspective view thereof;

FIG. 4 is a top plan view thereof;

FIG. 5 is a side elevation view thereof;

FIG. 6 is a perspective view of a second embodiment of the jewelry arrangement;

FIG. 7 is an exploded perspective view thereof; and

FIG. 8 is a side elevation view thereof;

FIG. 9 is a perspective view of a third embodiment of the jewelry arrangement;

FIG. 10 is an exploded perspective view thereof; and,

FIG. 11 is a side elevation view thereof.

The broken lines are provided for illustrative purposes only, and form no part of the claimed design. In addition, the portions of the jewelry arrangement that are not shown in the drawing do not form any part of the claimed design. The portions in the drawings that are provided in solid lines show and thus claim section(s) of the respective surface(s) of the jewelry arrangement.
